UNITED STATES PATENT OFFICE.

WILLIAM DUKE, SR., AND WILLIAM DUKE, JR., OF PHILADELPHIA,
PENNSYLVANIA.

PRINTING-GAGE.

No. 841,948.

Specification of Letters Patent.

Patented Jan. 22, 1907.

Application filed July 23, 1906. Serial No. 327,274.

To all whom it may concern:

Be it known that we, WILLIAM DUKE, Sr., and WILLIAM DUKE, Jr., citizens of the United States, residing in the city and county 5 of Philadelphia, State of Pennsylvania, have invented a new and useful Printing-Gage, of which the following is a specification.

Our invention consists of an improvement in a gage for setting sheets to be printed true 10 and uniform on the platen of the press, the novel features of the same being hereinafter described, and pointed out in the claims.

Figure 1 represents a perspective view of a gage for a printing-press embodying our invention. Fig. 2 represents a top or plan view thereof. Fig. 3 represents a longitudinal vertical section on line $x-x$, Fig. 2. Fig. 4 represents a similar section on line $y-y$, Fig. 2. Fig. 5 represents a similar section on line $z-z$, Fig. 2. Fig. 6 represents a section similar to that shown in Fig. 4 with the parts in different positions. Fig. 7 represents a horizontal section of a portion of the gage. Fig. 8 represents a top or plan view of the gage, on a 25 reduced scale, shown in operative position on the platen of a printing-press.

Similar letters of reference indicate corresponding parts in the figures.

Referring to the drawings, A designates a 30 base on which are mounted pairs of parallel cylinders B B and C C and the cylinders D D, one of the latter being interposed between the pairs of cylinders B and the other being interposed between the pairs of cylinders C. In each cylinder B C is the telescopic section 35 E, with which is connected the plunger F.

Secured to the forward ends of the plunger of each pair of cylinders B is the cross-bar G, and secured to the plunger of each pair of 40 cylinders C is the cross-bar H, it being noticed that said cross-bars G and H are on opposite sides of the center of the gage.

Projecting forwardly and outwardly from what may be termed the "front" of the gage 45 are the prongs or fingers J, which are somewhat sharpened or pointed, so as to readily enter the tympan-sheet, it being noticed that the bars G and H are recessed, as at K, whereby said bars in their motions may 50 readily slide over said fingers.

In the cylinders D are the telescopic sections or plugs L, from which extend the plungers or rods M, which pass through said cylinders D, within which are the springs M', 55 which bear against said sections L and the

ends of said cylinders as abutments, said springs thus forming resilient resistances for said sections when the toggle-levers are lowered, permitting, however, said sections and the plungers M to continue their motions 60 when the registering-bars H are seated in a direction the opposite to said bars, said springs afterward assisting to restore the movable parts to their normal positions.

P designates springs which are fitted on 65 the plungers F and bear at their ends against the telescopic sections E, as shown, and the end of the cylinders B C, respectively. On the outer ends of the plungers F are nuts Q, which are adapted to bear against the telescopic sections E in order to adjust the position 70 of the relative parts and the tension of the springs P. On the outer ends of the plungers M are nuts N, which are adapted to bear against the adjacent ends of the cylinder D in order to adjust the position of the relative parts and the tension of the springs M'.

R designates toggle-levers the limbs of which are pivotally connected with the adjacent bars G and H and the telescopic section of the cylinders D, respectively, it being noticed that said levers rise where pivotally joined together, so that the joints of the members of the levers are at the apices of the levers. 85

Mounted on the base A, at the center thereof, between the respective cylinders B C, is the elbow-lever S, the upper limb of which rises above the top of the levers R. Connected with the limbs of said lever S at the 90 joint thereof is the spring T, the object of which is to hold the upper limb elevated and salient, as most clearly shown in Figs. 3 and 5.

The operation is as follows: When the reglet or other proper part of the press is lowered, it bears against the upper limb of the lever S as the primary pressure occurs, thus lowering said lever and placing it in contact with the paper for primarily holding the same. As the reglet continues its descent it bears against the joint or top portion of the toggle-levers R as the secondary pressure device, thus straightening said levers, and consequently advancing the bars G and H, the latter contacting sidewise with the edge of 100 the paper, bearing against the same, so that as the paper moves under the contact part of the lever S it is placed true on the tympan-sheet, it being noticed that the bars G and H, whose motions in the present case, as shown 110

in Figs. 6 and 7, are to the right, come to a dead stop against the paper before printing; but the toggle-levers continue to descend, this being permitted, as there is an excess of motion of the limbs of said levers—in the present case those on the left-hand side of said Figs. 6 and 7, after the bars G and H come to a dead stop, before the limbs of said levers reach the plane of the tubes B and C. Consequently said sections L and the plungers M move to the left. In the motions of the plungers they compress the springs M', whereby the latter exert a pressure against the connected parts to assist in retaining them in the positions they now assume, while they also provide a resilient resistance to said plungers, which avoid strain on and breakage of said parts as the latter are operated. When the reglet rises, it releases the toggle-levers and elbow-lever S; when the springs M', P, and T serve to return the bars G and H and elbow-lever S to their normal positions.

Having thus described our invention, what we claim as new, and desire to secure by Letters Patent, is—

1. In a gage of the character stated, a primary pressure device, a secondary pressure device, and compressible means for actuating each of the pressure devices one after the other by direct engagement therewith of a movable member of a press.

2. In a gage of the character stated, a primary pressure device, a secondary pressure device, compressible means for actuating each of the pressure devices one after the other by direct engagement therewith of a movable member of a press, and means for returning said devices to their normal positions.

3. In a gage of the character stated, a registering-bar, a toggle-lever having one limb connected therewith with its joint in position to be directly engaged by a movable member of a press, members telescopically fitted to each other, the movable member thereof being connected with said limb, means for returning said movable member and consequently said bar to its normal position, a primary pressure device, and an actuating member therefor independent of said toggle-lever.

4. In a gage of the character stated, a primary pressure device, a registering-bar independent thereof, a toggle-lever connected with said bar, a guided member connected with said lever, and means independent of the said pressure device for guiding said bar.

5. In a gage of the character stated, a primary pressure device, a registering-bar independent thereof, a toggle-lever connected with said bar, a guided member connected with said lever, means independent of the said pressure device for guiding said bar, and means for returning said lever and consequently said bar to normal positions.

6. In a gage of the character stated, a registering-bar, a lever connected therewith, a movable piece with which a limb of said lever is connected, a tubular guide for said piece and a plunger on said piece, said plunger being adapted to pass freely through an end of said guide.

7. In a gage of the character stated, a registering-bar, a lever connected therewith, and disposed in position to be directly engaged by a movable member of a press, means for guiding said bar and lever, an endwise-compressible spring for returning said lever to its normal position, means for adjusting the tension of said spring and means permitting movement of the lever after the movement of the bar ceases.

8. In a gage of the character stated, a registering-bar, a toggle-lever pivotally connected therewith and disposed in position to be directly engaged by a movable member of a press, a movable piece attached to a limb of said lever and a guide for said piece.

9. In a gage of the character stated, a registering-bar, a toggle-lever pivotally connected therewith and disposed in position to be directly engaged by a movable member of a press, members telescopically fitted to each other, one limb of said lever being attached to one of said members, a spring engaging said members to return said lever and bar to their normal positions.

10. In a gage of the character stated, a primary side pressure device and a secondary pressure device parallel therewith and arranged to be directly engaged by a movable member of a press after said member has engaged and actuated the primary side pressure device, the latter independent of and on the side of said primary pressure device.

11. In a gage of the character stated, a registering-bar, a toggle-lever connected therewith, means for operating said lever to lower the same, a movable piece with which a limb of said lever is connected, a guide for said piece, a resilient resistance device for said piece and an abutment for said device whereby when said bar is moved to operative position, said piece and connected parts are adapted to continue their motions in the direction opposite to that of said bar.

12. In a gage of the character stated, a primary pressure device, a secondary pressure device independent thereof, and independent actuating means for said devices arranged in different vertical planes to be independently directly engaged in succession by a movable member of a press.
